UNITED STATES PATENT OFFICE.

ROY A. GERMAN AND ALBERT C. ERNEST, OF WACO, TEXAS.

SQUARE.

Application filed April 17, 1922. Serial No. 553,904.

To all whom it may concern:

Be it known that we, ROY A. GERMAN and ALBERT C. ERNEST, citizens of the United States, residing at Waco, in the county of McLennan and State of Texas, have invented new and useful Improvements in Squares, of which the following is a specification.

Our present invention has reference to a combination instrument for use by mechanics.

The primary object of the invention is to produce a protractor or gauge for use by carpenters in cutting the rafters for a building roof which will obviate the use of the ordinary carpenter's square in determining the angles at which the rafters are to be cut and which will further obviate the necessity of a carpenter making calculations.

A further object is to produce in a single instrument, a rule, a bevel, a level, a square, a protractor, a roof framer, a caliper, a compass, an ordinary gauge, and a pulley and mortise gauge.

The foregoing objects may be accomplished by a construction such as is disclosed by the drawings which accompany and which form part of this specification.

In the drawings:

Figure 1 is a plan view of an instrument embodying the present invention showing the same in the nature of a square.

Figure 2 is a similar view looking toward the reverse side of the instrument.

Figure 3 is a plan view showing the manner in which the instrument can be employed as a pulley gauge or compass.

Figure 4 is a sectional view on the line 4—4 of Figure 1.

Figure 5 is an edge elevation of the device.

Figure 6 is an edge elevation of Figure 1.

Figure 7 is an elevation of one of the parts embodying the invention.

Figure 8 is a detail view.

Our improvement includes primarily a stock 1 and a blade 2. The stock is centrally slotted from one of its ends for the major portion of its length, the blade being received in the slot and being pivotally connected thereto by a preferably threaded element 3 that is engaged by a nut 4. By turn-

ing the element 3 to cause the shank thereof to engage the threads of the nut the head portion of the said element will bind upon one of the sides of the stock, compressing both sides of the said stock and binding the blade therebetween, and whereby the said blade may be retained at desired angles with respect to the stock.

The stock, on one of its faces has a comparatively wide depression of a length slightly less than that of the stock, the side walls formed by the depression being beveled inwardly, and the said depression providing a pocket 5 for a rule 6 Figs. 1 and 4. The rule has its edges beveled outwardly and being of a width corresponding with that of the pocket, the said edges are designed to engage with the inclined side walls of the said pocket and by virtue of the friction exerted by such engagement, the rule is normally held in the pocket and likewise properly held when partly withdrawn from the pocket. In this manner, the rule can be employed as a gauge in connection with the straight end of the stock. Likewise, the rule may be wholly withdrawn from its pocket when desired for measuring.

On its opposite face, the stock is formed with a similar but narrower depression forming the same with a pocket 7, and the side walls of this pocket are also preferably beveled inwardly. The pocket 7 receives therein a rule 8 which has its edges beveled outwardly to exert a frictional engagement with the side walls of the pocket. The rule 8, at its outer end has a right angularly arranged finger 9, and the stock 1 has its outer end provided with a notch 10 Fig. 6 to receive the finger therein, when the rule is fully received in the pocket 7. The rule is provided with a depression forming a finger hold 11, and the rule 6 has a central depression 12 for the thumb of the operator in withdrawing or partly withdrawing the rule from the pocket 5.

The finger 9 on the rule 8, in combination with the outer and straight end 13 of the stock provides the device with a caliper which may be employed for measuring the thickness of plates, pipes, rods, etc. The stock has on what I will term its inner face

a depression or pocket in which is seated a bubble glass 14, so that the stock can be employed as a level.

The blade 2 has its corner beyond its pivot rounded and formed with a right angular extension 15 Fig. 7, the inner edge between the extension and blade proper being formed with a diagonal brace at an angle of approximately 45° and is indicated in the drawings by the numeral 16. Above the edge of the brace 16 the blade has inscribed on one of its faces the pitch or rise of rafters or other materials to be cut. On the blade, outward of the said inscriptions, degree lines are inscribed, the same being arranged on both sides of the blade and being continued along the outer edge 16, of the lower straight edge 17 Fig. 3 provided by the extension 15, and the outer edge of the extension. These degree marks are broadly indicated by the numeral 18, and on the face A Fig. 2 of the blade outward of the degree marks 18 thereon there are arranged in spaced columns, disposed opposite the rise and pitch inscriptions, numerals whereby the degrees of different cuts of rafters may be obtained without mental calculation. On the face B, Figure 1, the inscription reads from the outer to the inner edge—

- 30 "Rise or pitch.
Common rafter bottom and top cut.
Hip rafter bottom and top cut.
Octagon hip rafter bottom and top cut.
Side cut of jack rafters.
35 Side cut of hip on ridge.
Side cut of sheeting.
Side cut of octagon sheeting.
Side cut of octagon jacks."

As stated, in a line with these are the columns of figures, and we will suppose that a common rafter is to be cut with an 8-inch rise. We therefore look for the character 8 in the upper numeral column and then look for the column for the top and bottom cut of the common rafter, and will find directly below the numeral 8, the numeral 34. The blade is then turned until the degree mark 34 is brought in a line with the inner edge of the stock and the top and bottom cut of the rafter and the notch for the plate is thus obtained. For hip rafters, the same method is employed, and at the third line, the character 25 will be found, the blade being set at 25° which gives the top and bottom cut of the hip rafter and also the notch for the plate. The side cut for the jack rafters and the side cut for the hip and ridge rafters are all obtained in the same manner.

60 The inscription on the face A of the blade reads from the outer to the inner edge of the blade—

"Pitch or rise.

Length of common rafter per running foot.

Length of hip rafter per running foot.

Length of first jack 16 in. center.

Length of first jack 24 in. center.

Backing of hip rafter.

Side cut of purline.

Side cut of polygon.

Miter cut of polygon,"

and outward of the degree marks on the said face A of the blade numerals and fractions thereof arranged in columns opposite the referred to inscriptions. To obtain the length of a common rafter, we will suppose that the building is 16 feet wide and that the rafter will reach only one-half way across the building and is therefore 8 feet in length. We have 8 inch rise on a one-third pitch and we will find under the character 8 in the numeral column, the figure $14\frac{2}{3}$, which is the length of the common rafter per foot run. At 9 inch rise we will have 15 inches if the building is 16 feet wide, and therefore will step off 8 times 15 inches which gives us the length of the rafters at 9 inch rise. We obtain the length of the hip rafter in the same manner. We will suppose the length of the first jack rafter is 16 inches center. We will find under 8 or whatever rise we desire; $19\frac{1}{4}$ inches which is the length of the first jack. When the length of the first jack is 24 inches center we mark off the same in inches and for the length of the first jack under 8 we will find on the blade $28\frac{2}{3}$ inches length.

The extension, the straight lower end thereof and the outer inclined portion between the last mentioned portion and the blade proper are all spaced away from each other and the inner edge of the said extension is provided with spaced notches 19, Figure 3 and the portion 17 between the extension and the beveled portion 16 is provided with spaced holes 20. The extension may be likewise provided with one or more holes 21. The notches 19 are inscribed with fractions of inches, and by placing the pencil through the holes 20 which are $\frac{1}{8}$ of an inch apart, proper markings for pulleys can be obtained, as can a gauge for mortising by placing a pencil in any of the openings 20 or 21 or in any of the notches 19.

The improvement may, of course, be employed as a square, and from the foregoing description, when taken in connection with the drawings, it is thought the construction and advantages of the device will be apparent to those skilled in the art to which this invention relates, and that further detailed description will not be required.

Having described the invention, we claim:

In a device of the class described, a slotted stock having straight edges, a blade received in the slot of the stock and piv-

totally clamped thereto, said blade having an extension substantially in the form of a right angle triangle, the outer portion of which being straight and parallel with the 5 blade, said extension being provided on its outer edges with degree marks and the blade having similar degree marks, and said marks designed to register with the edge of the stock when the blade is swung through the stock, said extension having 10 spaced apertures therethrough, one edge of its outer member provided with substantially V-shaped notches and a scale whose division marks register with the notches.

In testimony whereof we affix our signatures.

ROY A. GERMAN.

ALBERT C. ERNEST.
